UNITED STATES PATENT OFFICE.

GEORGE WASHINGTON EBRIGHT, OF XENIA, OHIO.

DISPLAY-HOLDER FOR HANDKERCHIEFS, &c.

No. 802,802.

Specification of Letters Patent.

Patented Oct. 24, 1905.

Application filed November 3, 1904. Serial No. 231,293.

To all whom it may concern:

Be it known that I, GEORGE WASHINGTON EBRIGHT, a citizen of the United States, residing at Xenia, in the county of Greene and State 5 of Ohio, have invented a new and useful Improvement in Display-Holders for Handkerchiefs, &c., of which the following is a specification.

My invention is in the nature of a novel form of holder for displaying in suspended position handkerchiefs, neckties, ribbons, laces, and other similar articles of merchandise in stores in such a way as to exhibit the patterns of the same in an attractive way, to hold a large quantity of them in available position for sale, and to so secure them as to permit them to be inserted and removed with great facility and without danger of tearing or soiling the delicate fabrics.

My invention consists in the novel construction and arrangement of the holder, which I will now proceed to describe with reference to the drawings, in which—

Figure 1 is a side view; Fig. 2, a plan view; Fig. 3, an enlarged detail in plan view of a portion of one of the holder-arms, and Fig. 4 is a cross-section of the same.

In the drawings Figs. 1 and 2, A represents a vertical shaft bearing at its lower end a series of horizontal radial arms B, whose outer ends are attached to and sustained by individual guy-wires C, extending up and inwardly to the central shaft, to which they are attached. The shaft A is preferably suspended from its upper end, but may be sustained in any other way. The radial arms B and guy-wires C are preferably arranged to revolve about the shaft A.

The construction of the arms B constitutes the chief feature of my invention, and this is best seen in Figs. 3 and 4. Each arm is formed of two longitudinal strips b and b' of wood or metal, which are fastened together by screws or otherwise and clamp between them a series of wire clasps c of peculiar character, as hereinafter more fully described. The upper one of the two longitudinal bars is about half as wide as the lower one and is centrally placed thereon for the purpose hereinafter described. The wire clasps c are of symmetrical and integral construction and extend in two rows or series, one on each side of the arm-strips b b' in parallel position throughout the length of the arm. They 55 are formed of a single piece of spring-wire

of round or other cross-section and are bent into elongated hexagons, the inner angle of each hexagon extending across the bar b and being more elongated than the outer angle. The parallel sides of the hexagon lie 60 parallel with and adjacent to each other—that is to say, the side 23 of one hexagon lies adjacent to, parallel with, and normally in contact with the side 56 of the next adjacent hexagon on the same side of the arm, and 65 these two flat and straight sides form elongated pinching-surfaces between which the ends of the handkerchiefs or other articles are clamped and held without concentrating the pinching strain at any one point. This 70 latter would be objectionable, as it would be likely to tear any delicate fabric if held at a single definite point in contradistinction to the broad flat jaws which my elongated hexagons afford and which do not injure the most delicate fabric, and yet sufficiently hold the articles in suspended position. As the fabric of the article is forced in between the parallel sides of the hexagons the outer and inner angles 4 and 1 of the hexagon becomes somewhat more acute and the clasp-loops slightly elongated, which gives great elasticity to the clasps and further conserves the security and safety of the fabric and the parallelism of the sides 23 and 56. 80

Another feature of my invention is to be found in making the two bars b and b' of different widths. The elongated hexagons, it will be seen, project at right angles to the arms and spring upwardly more easily than 90 they do downwardly. This is because when the clasps spring up they bend about a long radius having its center at x against the narrow strip b'; but when sprung downwardly they bend downwardly about a shorter radius having its center at y against the broader and lower strip b. Furthermore, the two legs of the hexagon are closer together at x x than they are at y y. This further contributes to the different elasticity of the clasps as between 95 an upward and a downward strain. The value of this will be seen when it is understood that the tip of the handkerchief is inserted between two adjacent clasps by an upward movement which permits easy insertion by reason of the increased flexibility in this direction, while for the downward strain the handkerchief is held more securely. The outer angles 3 4 5 of the hexagons form between them reentrant angles which afford throats to guide the fab- 100 105 110

ric in inserting the same, and the inner angles 2 1 6 extend all the way across the broader clamp-bar *b*.

In forming up the clasps from a single 5 piece of wire this is cheaply done on a machine, and the wire clasps are afterward inserted between and held by the clamp-bars. In folding and bending the wire all the lines 10 are straight lines, which makes the construction of dies easier, and the elongated hexagon on one side runs into and continues as a part of the elongated hexagon on the other side, so that the two series of clasps are continuous and symmetrical.

15 I am aware that a whip-rack has been formed of two clamp-bars holding between them a series of loops formed by a continuous piece of wire, there being no hexagonal form to the clasps and no broad clamping-jaws, but only 20 a V-shaped angle and no differential elasticity of loops, as between the upward and downward strain, and I make no claim to any such construction as exists in said whip-rack.

I am also aware that a necktie-holder has 25 been made with a series of parallel U-shaped wire loops, and I do not claim this construction.

30 My invention is distinctive in its hexagon shape of loop having an inner convergence as well as an outer convergence, which causes the loop to elongate and the sides to remain parallel when the articles are inserted between and also is distinctive in the differential elasticity of the loops as between the upward and 35 downward strain.

My holder with clasp-loops of hexagonal 40 form is very cheaply constructed and forms a safe and efficient means for holding delicate fabrics of dry goods—such as handkerchiefs, neckties, ribbons, and laces—and which gives 45 a handsome and dressy effect to the counters

and at the same time fully displays the patterns and colors of the fabrics. The handkerchiefs are quickly and safely removed by a light downward and outward pull, as wanted, and the multiple construction of the clasps permit of indefinite extension and large storage capacity.

In supporting the radial arms of the holder I have shown them connected to guy-wires *C*, which enable them to carry a greater weight; but as the weight to be carried is inconsiderable these guy-wires in many cases will be dispensed with.

Having thus described my invention, what I claim as new, and desire to secure by Letters Patent, is—

1. A display-holder for fabrics consisting of a series of elastic hexagonal loops having their parallel sides adjacent to each other, each loop having an angular converging inner portion and an angular converging outer portion, and retaining-bars for the same extending transversely to the loops substantially as described.

2. A display-holder for fabrics consisting of two clamping-bars, and a series of loop-shaped spring-clasps secured between the said clamping-bars and having the bearing edge of one bar closer out to the free end of the loop than the bearing edge of the other bar, substantially as and for the purpose described.

3. A display-holder for fabrics consisting of two clamping-bars of different width centrally placed in relation to each other, and a double series of spring-loops secured between said bars, said loops being formed of spring-wire running alternately from one side of the bars to the other substantially as described.

GEORGE WASHINGTON EBRIGHT.
